UNITED STATES PATENT OFFICE.

WILLIAM ERASTUS WILLIAMS, OF CHICAGO, ILLINOIS.

DISK WHEEL.

1,405,648.

Specification of Letters Patent. Patented Feb. 7, 1922.

Application filed June 23, 1921. Serial No. 479,946.

To all whom it may concern:

Be it known that I, WILLIAM ERASTUS WILLIAMS, a citizen of the United States, a resident of Chicago, in the county of Cook 5 and State of Illinois, have invented a new and useful Improvement in Disk Wheels, of which the following is a specification.

My invention relates to automobile wheels that are made of pressed metal and that 10 type of wheel which demounts the disk in a quick change of tires, instead of demounting the rim as has heretofore been the practice.

The object of the invention is to provide the cheapest and most serviceable wheel pos- 15 sible and one in which the disk may be easily detached and affixed to hubs of the type used with wheels having wooden spokes.

Reference will be had to the accompanying drawings in which Figure 1 is a front 20 elevation of the wheel.

Figure 2 is a transverse sectional view on a larger scale than that of Figure 1.

Figure 3 shows a section on line 3—3 of Figure 1, indicating the valve opening.

25 Figure 4 is a sectional detail on line 4—4 of Figure 2.

Figure 5 is an alternative construction showing a variation in the disk fastening to the rim from that shown in Figure 4.

30 Figure 6 is a modified form of the fastening of the disk at the hub.

Figure 7 is still another modified form of the disk fastening at the hub.

35 Figure 8 is a sectional detail for a short distance around the hub on the circle indicated by the arrow "a."

In the drawing 1 indicates the ordinary clincher rim and 2 indicates the ordinary hub used with the wooden wheel which is 40 provided with the hub flange 3 integral with the hub and to this hub flange 3 the ordinary brake drum 4 is attached.

I provide what I term a hub zone flange indicated by 5 which is considerably larger 45 in diameter than the hub flange 3. This hub zone flange 5 is turned over into a bearing flange 6 on to the hub barrel 7 and is pressed outwardly to form an annular rib 8 which furnishes a seat 9 for the main sup- 50 porting disk of the wheel.

The rib 8 is interrupted at four different points by a stiffening depression or corrugation 10 which extends only for a short distance as indicated by the dotted lines in 55 Figure 1. This hub zone flange terminates

in an inclined flange 11 which also furnishes a seat for the main disk. The main disk is indicated by 12 and has a bearing surface 13 which rides on the surface 9 of the hub zone flange and it also has an inclined surface 14 60 which rides on the inclined margin 11 of the hub zone flange 5. The hub zone flange 5 is secured to the flange 3 of the hub by a series of bolts 15. The main disk 12 is here shown as being curved inward as indicated 65 by 16 in the zone outside of the hub zone flange and it extends out and simulates in appearance the front face of the felloe in the marginal region 17, and from this zone 17 the edge of the disk is turned over into the tread 70 seat flange 18.

The rim 1 is of the clincher type as here shown and it is provided with an internally extending bead 19 pressed inwardly from the flat stock of the rim. However, in some 75 instances this feature is a rolled integral bead or tire seat instead of an embossed rib as indicated by 19. The main disk 12 is secured to the hub zone disk 5 by means of screws 20 engaging nuts 21 secured to the 80 hub zone disk by some small flanges 22 and by rivets 23 to the hub zone disk 5.

The main disk is shown in Figures 2 and 7 as extending downward and terminating near the hub barrel in a little flange 24 and 85 the hub zone of this part of the disk is here shown in the said Figures 2 and 7 as being stiffened by a rib 25, but this form of the disk is optional. The preferred form is indicated by Figure 7 wherein the disk 12 is 90 turned over and terminates on the diameter indicated by 26 (see Figures 1 and 6). In the case of Figures 2 and 7 the hub bolts 15 are covered up by the hub zone section of the main disk 12 but in the case of the preferred form of Figures 1 and 6 these hub 95 bolts are exposed from the outside.

Thus the load of the entire wheel is borne by the hub zone flange 5 on the seats 9 and 11 and the bolts 20 hold the main disk 12 to this hub zone flange 5 and in a demounting change of tires only the bolts or screws 20 are released as the hub zone flange 5 is intended to be bolted on permanently to the hub. At the region of the bolts 20 there is a 10 narrow space 27 between the metal of the hub zone flange 5 and the main disk 12 in order to allow the bolts 20 to securely clamp the main disk and the hub zone flange to the seats 9 and 11 before mentioned. 11

The flange 18 of the main disk 12 is pressed tightly into the rim or the rim is shrunk on to it in the same manner that a felloe band is put upon the felloe of a wooden wheel. Owing to the shoulder 19 at the front the rim 1 may not be pressed off from the disk inward toward the vehicle and to prevent any possibility of the rim being pressed off outward from the vehicle I employ 10 a series of little indentations around the margin of the flange 18 and into the metal of the rim 1 as indicated by 28 and these indentations occur in about a dozen different places, depending on the wish of the manufacturer, around the circumference of the wheel and as they are of only short length the metal of the rim is swaged outward with a punch and the metal of the flange 18 swaged inward into the recess 20 formed in the metal of the rim without effecting a puncture of the metal of the rim 1 itself. These operations may be done very quickly and thus a secure fastening of the disk into the rim obtained.

25 Instead of relying on the indentations 28 to hold the disk 12 with its flange 18 in the rim I may rivet those parts together as is indicated by the rivets 29 in Figure 5 or in place of the rivets 29 I may spot weld 30 through these parts as desired or I may weld a little seam or a few spots along the edge of the flange 18 as indicated by 30 in Figure 5 or I may rely entirely upon the frictional contact between the rim and the flange 18 of 35 the disk in the same manner that iron tires or felloe bands are applied to wheels generally by pressing or shrinking them on as may be desired.

An indentation 31 is made for a short distance in the marginal zone of the disk to facilitate access to the valve stem for the pneumatic tube of the tire shown in dotted lines 33 in Figure 3. A hole 32 in the rim 1 and flange 18 of the main disk permits the 45 entry of the valve stem 33 indicated by the dotted lines and a hole 34 in the main disk allows this valve stem to protrude for access from the outside, so that the air may be applied and the amount of this volume measured 50 from the front face of the wheel.

In Figure 7 the main integral flange of the hub is at the front face of the wheel as is indicated by 35 and in this case the hub zone flange 5 is separated from the integral flange 55 of the hub 35 by a filler or spreader ring 36 and in this construction there will always be used the hub zone of the main disk 12 as is indicated by 37 in order to cover up the void spaces of 38 and 39 occasioned by using 60 with this type of a hub a disk wheel instead of spokes, as the brake drum 40 must be supported in the normal way to accommodate the wooden spokes on any interchange work as this type of a wheel for the spokes of a 65 wooden wheel on the same hubs. The hub

bolts 41 here used are longer than the hub bolts 15 used with the other design. The hub zone flange 5 is stiffened by a series of radial corrugations 42 which lie between the bolts 15, extend across the zone, and prevent 70 its buckling where it is not directly held by the bolt heads.

Filler blocks 43 of sleeve-like form are shown as filling out the hub barrel diameter in Figure 2 and a similar ring indicated by 75 44 is shown in Figure 7. However, in some instances annular filler rings 43 and 44 will be omitted.

In this construction the hub zone flange 5 virtually carries the hub outward to a diameter sufficiently large to permit the main disk 12 to be made of considerably lighter metal, as the fastening between the two disks is made also on this larger diameter as indicated by the location of the bolts or screws 20. 80

Thus by this construction I arrive at almost the same results in disk wheels that is secured by using disks having tapering sections and yet use the ordinary uniform thickness of metal which is a great desideratum. 90

The main lateral load strains thus come upon the main disk materially outside the hub proper, so that but for appearance the main disk might terminate at the circle of 95 the filler 26.

That main disk zone in which the bolts 20 lie is stiffened on each margin by the integral inclined portions 13, 14 so that the load on any bolt is partly transmitted to its 100 neighbors, the zone being practically unyielding radially. The space 27 ensures accurate contact at 9 and 14 whether or not the parts are primarily fitted accurately.

What I claim is:—

1. In a wheel of the class described, a hub having a flange integral therewith, a hub zone flange bolted to the said hub flange and provided with inclined seats on the margin of the said hub zone flange; in combination with a main disk secured in demountable fashion to the margin of the hub zone flange and provided with inclined seats adapted to seat upon the said hub zone flange and said disk suitably secured to a suitable rim. 105

2. In a device of the class described, a hub having a flange extending toward the rim for a relatively large area around the hub; in combination with a main disk the latter being secured to the margin of the hub flange 120 and the metal of the main disk being thinner than the major portion of the hub flange and with demountable means for securing the main disk to the margin of the hub flange, said main disk provided with a suitable tire 125 carrying rim.

3. The combination with a hub provided with an integral flange, of a hub zone flange secured to the flange first mentioned and having near its inner margin radial stiffening 90

corrugations and near its outer margin annular inclined bearing seats, and a main disk secured to the hub zone flange in the region of the inclined bearing seats and provided 5 with a suitable tire-carrying margin.

4. In a disk wheel of the class described, a hub, a tire carrying rim, a disk secured to the tire carrying rim and a hub zone disk secured to the hub, the said rim carrying disk and 10 said hub zone disk joined together in demountable fashion and at the margin of the hub zone disk, the metal of the rim carrying disk being thinner than the metal of the hub zone carrying disk and the disks together approximating the varying strength of a single 15 tapered disk.

5. The combination with a hub and a heavy hub zone disk extending to a material distance from the hub to receive the principal 20 lateral or skid strains, of a thinner, rim-carrying disk demountably fixed to the hub zone disk and extending outwardly therefrom to the rim region.

6. The combination with a hub and a rim, 25 of a hub zone disk having near its periphery a lateral seat, a rim-carrying disk fitting and

detachably fixed to said seat, and extending inwardly from said seat to cover the body portion of the hub zone disk.

7. In a device of the class described, a rim, 30 a disk forming the web of the wheel secured to the said rim by frictional engagement; in combination with a series of indentures made in the rim and into which the metal of the disk is swaged. 35

8. The combination with a hub zone disk provided with spaced, inclined annular bearing areas on one face, of a rim-carrying disk laterally overlapping the hub zone disk, fitting said areas and spaced from the hub zone 40 disk between said areas, and bolts passing through the disks between their contact-making areas and detachably binding the disks together. 45

Signed at Chicago, in the county of Cook and State of Illinois, this 13th day of June, 1921.

WILLIAM ERASTUS WILLIAMS.
